C. HASLAM

Des. 127,715

TEXTILE FABRIC OR SIMILAR ARTICLE

Filed April 9, 1941

INVENTOR:

Carl Haslam
BY Elizabeth C. Brown,
ATTORNEY.

UNITED STATES PATENT OFFICE

127,715

DESIGN FOR A TEXTILE FABRIC OR SIMILAR ARTICLE

Carl Haslam, New York, N. Y., assignor to Phoenix
Textile Printing Corp., New York, N. Y., a corporation of New York

Application April 9, 1941, Serial No. 100,265

Term of patent 3½ years

To all whom it may concern:

Be it known that I, Carl Haslam, a citizen of the United States, residing at New York city, in the county and State of New York, have invented a new, original, and ornamental Design for a Textile Fabric or Similar Article, of which the following is a specification, reference being had to the accompanying drawing, forming part thereof.

The figure is a plan view of a textile fabric or similar article, showing my new design.

I claim:

The ornamental design for a textile fabric or similar article, substantially as shown.

CARL HASLAM.
